CLAIM

The ornamental design for a clasp, as shown and described.

DESCRIPTION

FIG. 1 is a front left perspective view of the clasp in a handbag environment and in a closed position;
FIG. 2 is a front left perspective view of the clasp in the handbag environment and in an alternate, open position;
FIG. 3 is a front view of the clasp removed from the handbag environment and in the closed position;
FIG. 4 is a rear view of the clasp removed from the handbag environment and in the closed position;
FIG. 5 is a top view of the clasp removed from the handbag environment and in the closed position;
FIG. 6 is a bottom view of the clasp removed from the handbag environment and in the closed position;
FIG. 7 is a right-side view of the clasp removed from the handbag environment and in the closed position;
FIG. 8 is a left-side view of the clasp removed from the handbag environment and in the closed position; and,
FIG. 9 is a right front perspective view of the clasp removed from the handbag environment and in the closed position. The portions of the handbag and of the clasp shown in broken lines form no part of the claimed design.
